Primary Examiner — Richard Kearney*Assistant Examiner* — Qiawen W Wiechert(74) *Attorney, Agent, or Firm* — Robert F. Zielinski(57) **CLAIM**

The ornamental design for a chair as shown and described.

DESCRIPTION

FIG. 1 is a front perspective view of the chair of the present invention.

FIG. 2 is a top view thereof;

FIG. 3 is a right-side view thereof;

FIG. 4 is a front view thereof;

FIG. 5 is a left-side view thereof;

FIG. 6 is a rear view thereof; and,

FIG. 7 is a bottom view thereof.

In the drawings, the broken lines show portions of the chair that form no part of the claimed design.
